COUNTERBALANCE FOR VERTICALLY SLIDING DOORS

Herbert Cady Blodgett, Hartford City, Ind., assignor to Overhead Door Corporation, Hartford City, Ind.

Application May 29, 1939, Serial No. 276,370

14 Claims. (Cl. 20—20)

This invention relates to improvements in counterbalance for vertically sliding doors.

The main objects of my invention are:

First, to provide a counterbalancing mechanism 5 of the torsion type for vertically operated doors whereby the pitch lead of the counterbalance cable is automatically altered during counterbalancing of the door to enable the latter to be retracted further than has heretofore been possible.

Second, to provide a counterbalancing device for vertically operated doors, wherein the counterbalance unit is shifted automatically under the influence of the door movement.

15 Third, to provide a counterbalancing device which reduces the required head room in vertically sliding door installations.

Fourth, to provide the combination of a counterbalancing device having the advantages described above with a vertically operable door having an inclined vertical track.

20 Fifth, to provide a counterbalanced device which may be easily erected or assembled on vertically operating doors already installed, to enable the bottom section of the door to be raised 25 to a position above the header, thereby increasing the effective height of the door opening.

Further objects relating to details and economies of my invention will definitely appear from 30 the description to follow. The invention is defined in the claims.

A structure embodying the features of my invention is illustrated in the accompanying drawing, wherein:

35 Fig. 1 is a fragmentary view in side elevation of a vertically operating door installation provided with the counterbalance of my invention.

Fig. 2 is a fragmentary perspective view illustrating the details of the aforesaid counterbalance device.

40 Fig. 3 is a fragmentary view in vertical section, further illustrating the counterbalance device in operative relation to the vertically slideable door and clarifying the manner in which the counterbalance operates.

45 Fig. 4 is a fragmentary view in side elevation, illustrating a modified embodiment of my invention.

Fig. 5 is a fragmentary view in side elevation, 50 partially broken away and in vertical section, illustrating a still further modified, and preferred embodiment of a rolling counterbalance in accordance with my invention.

In present vertically operating door installations incorporating a door counterbalancing

mechanism of the torsion type, it is customary to mount the aforesaid mechanism in fixed relation to the door header and in a plane parallel to the header. Such installations are in general quite satisfactory, however they are characterized by the objectionable feature that since the relation of the counterbalance to the header is fixed, the operating or door elevating cables actuated by the counterbalance are only able to lift the door a certain distance, i. e., to a position where in the rollers on the lowermost door panel enter the curved portion of the track, whereupon the cables are ineffective to further the said panel due to the balancing of the component of vertical lifting forces exerted thereon by the reaction of the curved track to further vertical travel of the door when the cables are disposed at an angle to the vertical. This usually leaves the bottom panel of the door at a substantially lower elevation than the door header, with the result that the effective height of the door is decreased, or conversely, a greater door head room must be provided in order to secure a predetermined desired effective opening. My invention corrects this difficulty by substituting for the hitherto known fixed counterbalance, a counterbalance which is shiftably mounted relative to the header, being connected to the door in the usual manner, with the result that the counterbalance is automatically shifted rearwardly during the later period of the door operation, thereby maintaining the cable as it is trained over the front surface of the counterbalance in the vertical plane of its point of securement to the bottom door panel or section, with the result that the bottom door section is drawn up the curved track as far as possible.

The aforesaid automatically shiftable counterbalance has particular adaptability to a vertically operating door utilizing vertical tracks which are inclined slightly rearwardly relative to the door jamb, as illustrated and described in the patent to Johnson No. 1,820,195, dated August 25, 1931, such rearward inclination serving to automatically initiate the rearward shifting of the counterbalance in accordance with the present invention.

Referring to the drawing, the numeral 1 indicates a door frame, the header of which is indicated in dotted lines and identified by the reference numeral 2. This frame has secured thereto by the fixed brackets 3 a pair of vertically disposed and rearwardly inclined tracks 4, there being a track at each side of the doorway. The articulated door 5 is provided with rollers 6 at

the hinges thereof which travel in said tracks, the aforesaid rollers being spaced at increasing distances from the panels of the door vertically thereof, in order to enable a snug sealing fit of the door against the frame when the door is closed, as illustrated and described in the Johnson patent identified above. The tracks 4 include curved portions 7 which are secured by welding to angled brackets 8 bolted to the door frame adjacent the header 2 and the curved portions of the track terminate in horizontally disposed track portions 9, the latter being suitably supported at their rear ends. The door is receivable in these horizontal track portions in retracted position, as illustrated in Fig. 1.

The reference numeral 10 designates the winding drum of the torsion counterbalance mechanism which contains a pair of supports 11 for the usual torsion spring, the support shown being on a square spindle 12 extending through the end of the drum. This square spindle is received in a square aperture 13 in a swingable guiding and restraining arm or plate 14, thus preventing relative rotation of the shaft and arm, and the arm 25 has an elongated slot 15 slidably engageable with a limit pin or bolt 16 mounted on the bracket 8.

The reference numeral 17 designates the counterbalance cable which is connected at one end to the lowermost door panel in the usual fashion 30 and at the other end to drum 10.

I provide a counterbalance guide track in the form of a bar 18 which is suitably secured to the uppermost edge of the bracket 8 and extends rearwardly in parallelism with the horizontal track portion 9, being preferably bolted or riveted to the latter at 19. This guide track serves as a way for a grooved counterbalance guide roller 20, which roller is freely rotatable on a circular bushing or bearing 21 provided with a square aperture (not shown) receiving the square shaft 12. There is preferably a guide track 18 and guide roller 20 at each end of drum 10.

By the foregoing construction, it will be apparent that substantial angular movement of the squared shaft 12 is prevented by its engagement with the arm 14, while the grooved rollers 20 co-acting with guide tracks 18 permit the winding drum to be freely transported rearwardly.

In operation, when the door travels up the rearwardly inclined track, the lowermost panel thereof retreats rearwardly relative to the winding drum, assuming the latter to be in its original position illustrated in Fig. 1. This causes the cable to assume a rearward lead relative to the drum and a rearwardly directed component of force to be exerted on the latter with the result that the drum shifts rearwardly on the rollers 20, and the further result that the direction of the lifting action exerted on the lowermost panel of the door is maintained substantially vertical. As the track rollers enter the curved portion 7, the drum continues to shift rearwardly as illustrated in Fig. 3, and this shifting of the drum continues until the limit pin or bolt 16 reaches the end of the slot 15, at which time all portions of the door are elevated well above the header 2. The freely shiftable action of the counterbalance mount enables the door to be more readily lowered when desired.

In Fig. 4, I illustrate a modified embodiment of my invention, wherein the drum spindle 12 is mounted in angularly restrained manner in the swinging arms or plates 22 which are pivotally mounted at fixed points 23 on the angled brackets 8. The swinging plates 22 include laterally pro-

jecting stop lugs 25 engageable with the header 2 and fixed stops 26 on the counterbalance guide tracks 18 to limit the oscillating movement of the drum.

In operation, the embodiment of Fig. 4 is similar to that of Figs. 1 to 3, save for the fact that the drum is lifted slightly relative to the guide tracks 18 as it travels from front to rear and vice versa. This over-center action assures that the door will be maintained in its fully elevated and retracted position relative to the header until a definite and substantial downward force is exerted on the door.

In Fig. 5, I illustrate a still further modified embodiment of my invention, wherein the spindle 12 of the drum 10 is fixedly mounted on a carriage made up of a pair of spaced parallel plates 27 which overhang the counterbalance guide track 18 on either side thereof. A pair of carriage rollers 28 are rotatably mounted between the plates 27 on opposite sides of the drum 10. In this embodiment, it is obvious that the permissible movement of the counterbalance is limited only by the permissible rearward movement of the door itself, although it may be advisable to provide fixed stops 29 for the carriage on the tracks 18.

In each of the above described modifications, it should be noted that the slight rearward inclination of the tracks 4 is of substantial importance in the successful operation of the respective shiftable counterbalancing devices. It is evident that if the tracks did not incline rearwardly, the cable would be unable to come into effect in a manner to bias the winding drum rearwardly until the track rollers had at least entered the curved portion 7 of the tracks. It would not take a lead relative to the drum until that time. The shiftable feature does have advantages when embodied with tracks that are not inclined, but not the full advantages obtained with the inclined tracks.

I have illustrated and described my improvements in embodiments which are very practical. I have not attempted to illustrate or describe other embodiments or adaptations as it is believed this disclosure will enable those skilled in the art to embody or adapt my improvements as may be desired.

Having thus described my invention, what I claim as new and desire to secure by Letters Patent is:

1. In combination, a vertically operating door assembly including a pair of vertically disposed rearwardly inclined tracks having rearwardly extending horizontal top portions and an articulated door having rollers traveling in said tracks, and a counterbalance for said door, comprising a winding drum disposed transversely of the tracks, a lifting cable secured to said drum and to the door adjacent the bottom of the latter, means including torsion means for biasing the drum to elevate said cable, and means for mounting said drum for rearward shifting movement accompanying elevation of the cable and door, said cable assuming a rearward lead relative to the drum as the door travels upwardly in the inclined tracks to thereby exert a rearwardly directed force on the drum, and means for guiding said drum during the rearward shifting of the same in response to said force.

2. In combination, a vertically operating door assembly including a pair of vertically disposed rearwardly inclined tracks having rearwardly extending horizontal top portions and an articulated door having rollers traveling in said tracks,

and a counterbalance for said door, comprising a winding drum disposed transversely of the tracks, a lifting cable secured to said drum and to the door adjacent the bottom of the latter, means for biasing the drum to elevate said cable, and means for mounting said drum for rearward shifting movement accompanying elevation of the cable and door, said cable assuming a rearward lead relative to the drum as the door travels upwardly in the inclined tracks to thereby exert a rearwardly directed force on the drum, said drum shifting rearwardly in response to said force.

5. In combination, a vertically operating door assembly including a pair of vertically disposed

15 tracks and an articulated door having rollers traveling in said tracks, and a shiftable counter-

balance for said door, comprising a winding drum disposed transversely of the tracks, a lifting cable

20 secured to said drum and to the door adjacent the bottom of the latter, torsion means for biasing

25 the drum to wind the cable thereon and elevate said door, and means for mounting said drum for rearward shifting movement accom-

panying winding of the cable on the drum and

30 door, said cable assuming a rearward lead rela-

tive to the drum during said winding to thereby

exert a rearwardly directed force on the drum,

35 and means for guiding said drum during the rearward shifting of the same in response to said force.

3. In combination, a vertically operating door assembly including a pair of vertically disposed

40 tracks and an articulated door having rollers traveling in said tracks, and a shiftable counter-

balance for said door, comprising a winding drum disposed transversely of the tracks, a lifting cable

45 secured to said drum and to the door adjacent the bottom of the latter, torsion means for biasing

the drum to wind the cable thereon and elevate said door, and means for mounting said drum for rearward shifting movement accom-

panying winding of the cable on the drum and

45 door, said cable assuming a rearward lead rela-

tive to the drum during said winding to thereby

exert a rearwardly directed force on the drum,

50 and means for guiding said drum during the rearward shifting of the same in response to said force.

4. In combination, a vertically operating door assembly including a pair of vertically disposed

55 tracks and an articulated door having rollers traveling in said tracks, and a shiftable counter-

balance for said door, comprising a winding drum disposed transversely of the tracks, a lifting cable

60 secured to said drum and to the door adjacent the bottom of the latter, torsion means for biasing

the drum to wind the cable thereon and elevate said door, and means for mounting said drum for rearward shifting movement accom-

panying winding of the cable on the drum and

65 door, said cable assuming a rearward lead rela-

tive to the drum during said winding to thereby

exert a rearwardly directed force on the drum,

70 and means for guiding said drum during the rearward shifting of the same in response to said force.

5. A vertically operating door assembly com-

55 prising a door, a pair of vertically disposed and rearwardly inclined tracks, said door having

rollers engageable in said tracks to guide the

same for vertical movement, a torsion counter-

balance drum for the door, means for mounting

55 the drum transversely of the door adjacent the

door frame, said means including a rolling sup-

port for the drum which is freely shiftable in a

front to rear direction and vice versa, said drum

having lifting cables secured thereto and to the

60 door adjacent the bottom of the latter, and

means for resiliently biasing said drum in a di-

rection to elevate the cable and door, travel of

the door in said inclined track causing said cable

to assume a lead relative to the drum at its point

of attachment to the door and thereby exert

force on the drum tending to shift the same rear-

wardly, said rearward shift maintaining a sub-

stantial vertical lifting component effective on

the door.

6. A vertically operating door assembly com-

70 prising a door, a pair of vertically disposed and rearwardly inclined tracks, said door having

rollers engageable in said tracks to guide the

same for vertical movement, a torsion counter-

balance drum for the door, means for mounting

75 the drum transversely of the door adjacent the

door frame, said means including a pivoted sup-

port for the drum which is freely shiftable in a

front to rear direction and vice versa, said drum

having lifting cables secured thereto and to the

80 door adjacent the bottom of the latter, and

means for resiliently biasing said drum in a di-

rection to elevate the cable and door, travel of

the door in said inclined track causing said cable

to assume a lead relative to the drum at its point

of attachment to the door and thereby exert

force on the drum tending to shift the same rear-

wardly, said rearward shift maintaining a sub-

stantial vertical lifting component effective on

the door.

7. Counterbalancing device for a vertically op-

erating door, comprising a torsion counterbalance

drum disposed in a plane parallel to the door,

lifting cables secured to said drum and door,

and means for mounting the drum for lateral

movement in response to vertical actuation of

the door, comprising a carriage supporting the

drum, a fixed track projecting rearwardly rela-

tive to the door frame, and drum guide rollers

rotatably mounted in said carriage and travel-

ing on said track, said carriage and drum being

shifted laterally by reason of the lateral lead

assumed by the cable relative to the drum during

operation of the door.

8. Counterbalancing device for a vertically op-

erating door, comprising a torsion counterbalance

drum disposed in a plane parallel to the door,

lifting cables secured to said drum and door,

and means for mounting the drum for lateral

movement in response to vertical actuation of

the door, comprising a carriage supporting the

drum, and means for supporting the carriage

for lateral translation, said carriage and drum

being shifted laterally by reason of the lateral lead

assumed by the cable relative to the drum during

operation of the door.

9. Counterbalancing device for a vertically op-

erating door, comprising a torsion counterbalance

drum disposed in a plane parallel to the door,

lifting cables secured to said drum and door,

and means for mounting the drum for lateral

movement in response to vertical actuation of

the door, comprising a carriage supporting the

drum, a laterally fixed guide member, and guide

means on said carriage coating with said first named

guide member, said carriage and drum being

shifted laterally by reason of the lateral lead

assumed by the cable relative to the drum during

operation of the door.

10. A vertically sliding door assembly includ-

ing a torsion drum having a cable secured there-

to and to a vertically sliding door guided in a

track, and means for mounting said drum for

laterally shifting movement in response to move-

ment of the door, comprising a fixed bracket, and

an arm swingably and shiftably mounted on said

bracket and carrying said drum, the mounting

of the arm on the bracket being adapted to limit

the lateral shifting of the arm and drum, the

door cable biasing the drum laterally in the move-

ment of the door in the track.

11. A vertically sliding door assembly includ-

ing a torsion drum having a cable secured thereto

and to a vertically sliding door guided in a track

and means for mounting said drum for laterally

shifting movement in response to movement of

the door, comprising a mounting bracket, and an

arm pivoted to said bracket at a fixed point there-

on, said arm carrying said drum during move-

ment thereof laterally in response to movement

of the door in the track.

12. In a vertically acting door assembly, the combination of an articulated door, tracks therefor comprising rearwardly inclined vertical portions, horizontal top portions and rearwardly curved portions joining the vertical and horizontal portions, a counterbalance drum having torsion means housed therein, means for supporting said drum for lateral shifting movement, and a counterbalancing cable secured to the lower end of the door and to said drum, whereby the drum will automatically shift on its support by the shifting of the lead of the cable resulting from the opening and closing movements of the door.

13. In a vertically acting door assembly, the combination of an articulated door, tracks therefor comprising vertical portions, horizontal top portions and rearwardly curved portions joining the vertical and horizontal portions, a counterbalance drum provided with torsion means,

means for supporting said drum for lateral shifting movement, and a counterbalancing cable secured to the lower end of the door and to said drum, whereby the drum will automatically shift on its support by the shifting of the lead of the cable resulting from the opening and closing movements of the door.

14. The combination in a vertically acting door assembly of a door, tracks therefor provided with vertical portions and horizontal portions with intermediate rearwardly curved portions, a counterbalance drum mounted in a plane above the vertical portion of the track for shifting movement from front to rear, and a cable connected to the lower end of the door and windable on said drum, said drum being free to shift to maintain the angular relation of the cable relative to the drum.

HERBERT CADY BLODGETT.
